UNITED STATES PATENT OFFICE.

FREDERICK LEWIS MAITLAND BOOTHBY, OF TILFORD, NEAR FARNHAM, ENGLAND.

PROTECTION OF AIRSHIPS AGAINST FIRE.

Application filed February 2, 1924. Serial No. 690,205.

To all whom it may concern:

Be it known that I, FREDERICK LEWIS MAITLAND BOOTHBY, a British subject, residing at Tilford, near Farnham, Surrey, England, have invented certain new and useful Improvements in or Relating to the Protection of Airships Against Fire, of which the following is a specification.

This invention relates to the protection 10 of airships against fire and the means and methods whereby such protection is effected.

According to this invention I enclose, preferably completely, the gas bags of an airship, from the hull of which the cabin is 15 suspended, in an outer cover or covers, in order to provide a closed space around the gas bag or bags, which space I fill with gas, derived from the exhaust of the engine, which offers the advantage of maintaining, 20 by its moisture, the gas bags in good condition even in hot climates; it being well known that where the gas-bags are made of more than one material, e. g., cotton and gold-beater's-skin shrinkage at different rates and 25 cracking of one fabric occurs when taken from a moist atmosphere to a dry one.

This cover is provided with suitable 30 openings or connections for the admission and escape of the gas; while one or more conduits or trunks may be provided in the gas bag or between the gas bags and extending through the outer cover, preferably at the top for the escape of hydrogen gas from the bag or bags. Valves may be provided between the conduits and the interior 35 of the gas bag or bags and closable openings may be provided for the insertion of the hand for the purpose of adjusting the valves.

40 At the top of the airship cover a relatively large opening is provided for escape of the exhaust gas from the space between the gas bag and cover, and a lightly loaded valve may be provided in this opening. If it is desired that the valves and openings be placed in the lower part of the airship for 45 accessibility, this can be done and the exhaust gas may be led to them by trunks leading from the upper part of the airship.

50 Should an exhaust gas lighter than air be used, it would be introduced at the upper portion of the airship, the air displaced by it flowing out on the lower side of the air-

ship through a suitable opening or openings.

I first cool the gas, preferably by using it first for cooking and heating purposes, after which it may be passed through a filter or scrubber to remove dust and impurities—although this is not essential—and then admit it to the space between the gas bag and the outer cover. Alternatively, or in conjunction with the above, the gas may be cooled by passing it between two thin metal plates, the outer one forming part of the outer cover or plating of the ship and the inner one being lagged, if it is desired to prevent the heat passing to the interior of the airship.

The exhaust gas being heavy will tend to 70 accumulate in the lower portion of the protective space and the air therein will be gradually displaced and escape through an opening or openings in the top of the airship, provided for that purpose, and preferably through valves into the usual gas-bag trunks. When all the air has been thus driven out, the gas bag or bags will be surrounded by a layer of moist exhaust gas.

In descending, should the airship descend 80 at a greater rate than the exhaust gas can cope with, and the pressure between the outer cover and gas bag fall sufficiently, air will enter through the opening at the top, or alternatively air can be admitted 85 through suitable non-return valves provided for that purpose in the cover, or it may be blown or forced in from the slip stream of the propeller, or by a blower.

Should it be desired to remove some of 90 the exhaust gas contained in the cover to lighten the airship, or for other purpose, a valve at the lower side of the cover is provided so that the gas can escape or be driven out.

The fuel supply may be similarly protected by a cover containing non-flammable gas, or the fuel may be carried inside the outer cover surrounding the gas bags.

The accompanying diagrams show examples of the manner in which the invention is applicable to various types of airships.

Fig. 1 shows in elevation a typical form 100 of rigid or semi-rigid airship having its keel built below the frame of its hull, and

Fig. 2 is a cross-section thereof, on a

larger scale, at a point between two of its gas bags.

Figs. 3 and 4 are similar views of an airship of the rigid or semi-rigid type, with its keel built inside the hull, while

Figs. 5 and 6 represent in similar views an airship of the non-rigid type, and

Fig. 7 shows means for ensuring cooling of the non-flammable exhaust gas prior to its entry into the chamber provided for it.

In the airship illustrated in Figs. 1 and 2, the hydrogen gas bags A are located within the hull B the space between the outside of the gas bags A and the inner surface of 15 the hull B constituting a chamber C completely surrounding the several gas bags A. This chamber C is utilized for enveloping the hydrogen gas bags with the moist exhaust gas from the engines D, conducted by 20 conduits E, leading the gas along the keel B¹, through cooking apparatus as well as heating apparatus, which may be arranged in the car F, and thence to the chamber C.

Each of the gas bags A is provided with 25 the usual pressure controlling valve A¹ and a manœuvring valve A². The pressure controlling valves A¹ of adjacent gas bags can be opened to communicate with trunks or ducts A³ arranged between them through 30 which the released gases escape to the atmosphere. At their lower ends the ducts A³ are provided with sleeves A⁴ extending into the keel B¹, thus providing means of access to the valves A¹ for adjusting or 35 operating purposes. The manœuvring valves A² are arranged in ducts A⁵ forming passages through the chamber C from the gas bags A to atmosphere.

The chamber C is in communication with 40 the atmosphere by means of an outlet opening or openings C¹, which may be provided with a spring controlled non-return valve, through which the air is expelled by the heavier than air non-flammable exhaust gas 45 entering the chamber C, preferably near its bottom. A similar lightly loaded non-return valve C² is provided for admitting air to the chamber C, in the rigid type of airship, when, as for example in a quick 50 descent of the airship, the pressure of the non-flammable exhaust gas in chamber C drops below atmospheric pressure. If the non-flammable exhaust gas employed is 55 lighter than air, the said air outlet C¹ and inlet C² will be arranged on the underside of the hull. I also prefer to lead the exhaust gas into the trunks A³ in order that no explosive mixture may be formed therein on the escape of hydrogen through the 60 valves A¹.

The examples illustrated in Figs. 3 and 4 and in Figs. 5 and 6 show the adaptation

of the invention to airships of the semi-rigid and non-rigid type respectively, and the arrangements are substantially analogous to that shown in Figs. 1 and 2. In semi-rigid airships, having regard to the collapsible nature of the hull cover, however, it is here necessary, in order to maintain this cover inflated at all times, that the pressure in the chamber C be higher than the atmospheric pressure. For this reason the air outlet C¹ will always be provided with a spring loaded non-return valve, while it may not be advisable to rely entirely upon an automatic air inlet—as shown at C² Figs. 1 and 2 for the rigid type—under atmospheric pressure. The valve C² is therefore replaced by an air pipe G, to which air under pressure may be supplied by the slip stream of the propellers, or by pumping, in any suitable manner.

Fig. 7 shows a device by means of which cooling of the non-flammable exhaust gases prior to their entering the chamber C may be ensured. This device consists in a broad shallow channel H, through which the gas is conducted, before entering the chamber C, and which is formed between two parallel metal plates M, M¹ arranged flush with and as part of the hull cover B, preferably alongside of the slip stream of the propellers, and extending fore and aft for a suitable distance. A drain cock N enables the water of condensation to be drawn off to any desired place, and the inner metal plate M may be lagged to prevent the interior of the chamber from becoming heated.

What I claim and desire to protect by Letters Patent is:—

1. Means for protecting airships against fire comprising a plurality of gas-bags, an envelope surrounding the same, and means for introducing cooled but moist gas derived from the engine exhaust to said envelope.

2. Means for protecting airships against fire comprising a plurality of gas-bags, an envelope surrounding the same, valved trunks communicating with said gas-bags, and means for introducing cooled but moist gas derived from the engine exhaust to said envelope and said trunks.

3. Means for protecting airships against fire comprising a plurality of gas-bags, an envelope surrounding the same, means for introducing cooled but moist gas derived from the engine exhaust to said envelope, and means for introducing air to said envelope for the purpose described.

In testimony whereof I affix my signature.

FREDERICK L. M. BOOTHBY,
